(57) **CLAIM**

The ornamental design for a hair curling iron, as shown and described.

DESCRIPTION

FIG. 1 is a perspective view of a first embodiment of a hair curling iron showing our new design.

FIG. 2 is a front view thereof.

FIG. 3 is a rear view thereof.

FIG. 4 is a right side view thereof, the left side view being a mirror image of the right side view.

FIG. 5 is a top view thereof.

FIG. 6 is a bottom view thereof.

FIG. 7 is a perspective view of the hair curling iron of FIG. 1 shown in an alternate configuration.

FIG. 8 is a front view thereof.

FIG. 9 is a rear view thereof.

FIG. 10 is a right side view thereof, the left side view being a mirror image of the right side view.

FIG. 11 is a top view thereof.

FIG. 12 is a bottom view thereof.

FIG. 13 is a perspective view of a second embodiment of a hair curling iron showing our new design.

FIG. 14 is a front view thereof.

FIG. 15 is a rear view thereof.

FIG. 16 is a right side view thereof, the left side view being a mirror image of the right side view.

FIG. 17 is a top view thereof.

FIG. 18 is a bottom view thereof.

FIG. 19 is a perspective view of the hair curling iron of FIG. 13 shown in an alternate configuration.

FIG. 20 is a front view thereof.

FIG. 21 is a rear view thereof.

FIG. 22 is a right side view thereof, the left side view being a mirror image of the right side view.

FIG. 23 is a top view thereof; and,

FIG. 24 is a bottom view thereof.

1 Claim, 16 Drawing Sheets
